UNITED STATES PATENT OFFICE.

OTTO SCHRIEVERT, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

CIRCUIT ARRANGEMENT FOR WIRELESS SIGNALING.

Application filed December 27, 1922. Serial No. 609,214.

To all whom it may concern:

Be it known that I, OTTO SCHRIEVERT, a citizen of the Republic of Germany, and a resident of Hallesches Ufer 12/13, Berlin, 5 S. W. 11, Germany, have invented new and useful Improvements in Circuit Arrangements for Wireless Signaling, of which the following is a specification accompanied by drawings.

10 The present invention relates to the neutralization of the coupling between individual elements of a plurality of wireless senders working side by side. In accordance with the invention, the coupling between the

15 two sender systems is not entirely neutralized because this would often necessitate the provision of complicated and bulky arrangements. It has been found that in the practical operation of wireless telegraph apparatus it is often sufficient if the coupling is neutralized only in individual parts of the sender arrangements, and this is true particularly in case the coupling between the senders has in itself no harmful effects, e. g.

20 in the case of a coupling which does not reduce the radiation of the antennæ, but has the disadvantage that the respective senders cannot be adjusted independently of each other because the ammeter or the energy

25 30 generating element of each of the arrangements is affected by the currents in both arrangements.

An embodiment of the invention will be hereinafter set forth, first as applied to the 35 usual wireless telegraph arrangement in which two antennæ, which are provided on one and the same or on two towers located near each other, operate simultaneously and are closely coupled with each other. In accordance with prior inventions the coupling between the two antennæ may be entirely neutralized so that neither of the antennæ will be affected by current from the other antenna. However, for this purpose it is necessary that the extension self-induction coils of the two antennæ be physically 40 brought near each other. If the waves of the two antennæ are not very near each other, the reduction of the radiation of one antenna caused by the presence of the other antenna, will be hardly noticeable, and as far as purely electrical reasons are concerned, the complete neutralization of the coupling between the antennæ would not be advisable.

However, in view of the fact that the antenna is tuned in accordance with the ammeter, it has heretofore been necessary to neutralize, so far as practicable, the coupling between the antennæ because otherwise the ammeter of each antenna always indicated the currents of both senders.

In the drawing—

Fig. 1 is a diagrammatic representation of a portion of a circuit arrangement embodying the invention, and

Fig. 2 is a diagrammatic representation of a more complete circuit arrangement which also embodies the invention.

In accordance with one use of the present invention only the ammeters are uncoupled. 70 This is illustrated in Fig. 1. The coil L¹ of the sender S¹ receives induction from the sender S² and compensates thereby in the ammeter J¹ the current that flows from the sender S² in the antenna S¹. The antenna S¹ may therefore be adjusted exclusively to the current in its own circuit.

As a further exemplification of the present invention, Fig. 2 illustrates an application of the invention to a tube sender. In 80 this figure, the grid and anode of the tube R are coupled with the coil L¹. If the coupling between the two antennæ shown in Fig. 2 is not neutralized, then current will be received from the second sender in the anode 85 and the grid of the tube R, and the proper operation of the tube sender will be prevented.

In accordance with the present invention, the coil L¹ is connected in parallel with a 90 coil L² to which the sender S² supplies potential in such a manner that the coil L¹ is free from all currents except those of the operating frequency of the generating tube R. As indicated in Fig. 2 of the drawing, the ammeter J¹ of the sender S¹ may be located in the circuit of the sender S¹ in such a manner that the coil L² is connected in parallel with the ammeter J¹ as well as with the coil L¹.

Having described my invention, what I 100 claim is:

1. A circuit arrangement comprising two senders having their antennæ electrostatically coupled, and arranged to operate simultaneously, and means for neutralizing the effect of the coupling between the antennæ with respect to a part only of one of the senders, said means comprising a circuit con-

nected in parallel with said part and coupled with the other sender so as to receive compensating potential therefrom.

2. A circuit arrangement comprising two senders having their antennæ electrostatically coupled, and arranged to operate simultaneously, apparatus and also an ammeter connected in circuit with one of the senders, and means for neutralizing the effect of the coupling between the antennæ with respect to a part of said apparatus and said ammeter only, said means comprising a circuit connected in parallel with the said part and ammeter and coupled with the other sender.

3. A circuit arrangement comprising two senders having their antennæ electrostatically coupled, and arranged to operate simultaneously, one of said senders comprising an energy generator including a three-electrode vacuum tube, a coil in the anode circuit of the tube and a grid circuit regeneratively coupled with said coil, and means for neutralizing the effect of the coupling between the antennæ with respect to said energy generator, said means comprising a circuit connected in parallel with the coil in the anode circuit of the generator and being coupled with the other sender so as to receive compensating potential therefrom and transmit it to the first-mentioned sender.

4. A circuit arrangement comprising two senders having their antennæ electrostatically coupled, and arranged to operate simultaneously, apparatus and also a generator connected in circuit with one of the senders, and means for neutralizing the effect of the coupling between the antennæ with respect to a part of said apparatus and said generator only, said means comprising a circuit connected in parallel with said part and generator and coupled to the other sender.

5. A circuit arrangement comprising two senders having their antennæ electrostatically coupled, and arranged to operate simultaneously, and means for neutralizing the effect of the coupling between the antennæ with respect to a part only of one of the senders, said means comprising a circuit connected in parallel with said part and including a coil coupled with a coil on the other sender so as to transmit compensating potential from the last-mentioned sender to said part.

6. In combination, a plurality of circuits

having portions thereof coupled together, means for neutralizing the effect of the coupling between said portions on a part only of any one of said circuits.

7. In combination, a plurality of circuits having portions thereof electrostatically coupled together, inductive means for neutralizing the effect of the coupling between said portions on a part only of any one of said circuits.

8. In combination, a plurality of circuits having portions thereof coupled together, one of said circuits having a part which it is desired to keep free from the disturbing influence of the coupling with another of said circuits, said part having a neutralizing circuit connected across it and coupled with said disturbing circuit.

9. A circuit arrangement comprising two senders arranged to operate simultaneously with their antennæ electrostatically coupled together, the first sender having apparatus and a parallel circuit in series with its antenna, one branch of said parallel circuit containing an ammeter and generator and the other branch containing a neutralizing coil, said coil being coupled to the second sender so that the effect of the energy generated by said second sender on said ammeter and generator is nil.

10. A circuit arrangement comprising two senders having their antennæ electrostatically coupled and arranged to operate simultaneously, and means for neutralizing the effect of the coupling between the antennæ with respect to a part only of one of the senders, said means comprising a circuit connected in parallel with said part and coupled with the other sender so as to receive compensating potential therefrom, said part including a measuring instrument.

11. A circuit arrangement comprising two senders having their antennæ electrostatically coupled, and arranged to operate simultaneously, and means for neutralizing the effect of the coupling between the antennæ with respect to a part only of one of the senders, said means comprising a circuit connected in parallel with said part and coupled with the other sender so as to receive compensating potential therefrom, said part including a thermionic tube generator.

OTTO SCHRIEVER.
